UNITED STATES PATENT OFFICE.

JOHN B. MURPHY, OF HARTFORD, CONNECTICUT, ASSIGNOR TO THE NORTH AND PFEIFFER MANUFACTURING COMPANY, OF HARTFORD, CONNECTICUT, A CORPORATION OF CONNECTICUT.

BOOT OR SHOE CALK.

1,022,106.

Specification of Letters Patent. Patented Apr. 2, 1912.

Application filed November 15, 1911. Serial No. 660,381.

To all whom it may concern:

Be it known that I, JOHN B. MURPHY, a citizen of the United States, residing at Hartford, in the county of Hartford and 5 State of Connecticut, have invented certain new and useful Improvements in Boot or Shoe Calks, of which the following is a specification.

This invention relates to what I shall for 10 convenience term a "boot or shoe calk."

While a calk involving my invention is primarily intended for application to various kinds of footwear, it is conceivable that it can be employed with equal advan- 15 tage in other connections.

One of the principal objects I have in view, is to provide an article of the character noted which is strong in construction, capable of easy connection with a shoe or 20 other device, and which can be held in place in a solid and substantial manner.

The calk includes other features of utility which, with the foregoing, will be set forth fully in the following description wherein 25 I will outline in detail that form of embodiment of the invention which I have selected for illustration in the drawing accompanying and forming part of the present specification.

30 In the drawing the calk is shown in elevation and driven into a shoe (shown in section) which may be either the sole or heel thereof. As already intimated, however, the calk can be used in other ways. I desire it 35 also to be understood that I do not restrict myself to the particular showing made by said drawing and description; I may depart therefrom in several respects within the scope of the invention included in the claim 40 following said description.

The calk comprises a shank 2 and a point or foot 3, the major portion of the upper surface of said point or foot being preferably flat so that said foot or point can obtain 45 a solid, firm bearing upon the outer surface of a heel, sole or other part to thereby limit the vibration of the calk. The foot or point 3 comprises two portions 4 and 5, both of which are conical or on a downward taper, 50 the portion 5 being arranged above or behind the portion 4 and being of less pitch than the portion 4, by reason of which there is produced at the upper part of the point

a reinforcing or strengthening shoulder which, as will be evident, is close to the 55 shank 2 where additional strength is required. To further add to the strength of the device I form at the junction of the shank 2 and point 3 a fillet 6. The portions 4 and 5 are also connected by a fillet 7 60 which adds to the strength of the point or foot. The portion 4, as will be clear, is upon a very sharp or decided angle, and in the present case constitutes the penetrating part or point proper of the calk. 65

Preferably, but not necessarily, the shank 2 is upon an upward taper, and it is provided with a series of superposed circular or annular beads or ribs 8. These beads in the construction shown are frusto-conical in 70 shape, and in the present instance commencing with the lowermost one, they are of progressively decreasing diameter to thus conform approximately to the upward taper of the shank 2, as by tapering said shank I 75 find that it can be very readily driven in a previously formed hole which can be made with an auger or other suitable instrument. The lateral portions of the respective beads or ribs 8 are on a downward slant which is 80 less than that of the taper of the shank, while the under flat surfaces of said beads are at right angles to the longitudinal axis of the shank, by reason of which latter feature I can secure the maximum holding 85 effect of said ribs upon the wall of said previously formed hole. To further increase the strength of the calk I may form underneath each rib at its junction with the shank a fillet 9. 90

The head of the shank 2 comprises the cylindrical portion 10 and the cone pointed portion 11 surmounting the same or at the top of the shank. The part 12 in which the shank of the calk is driven may be the sole 95 or heel of a boot, shoe or any other article of footwear, or in fact any article with which a calk can be associated. Previously to applying the calk the part 12 has formed therein a hole, and into this hole the shank 2 100 is driven. By having the cone pointed upper end 11 the introduction or insertion of the shank into the said hole is materially facilitated. Preferably, but not necessarily, the diameter of the cylindrical portion 10 is 105 substantially the same as that of said hole,

so that when the shank is in place or has been driven home, the surface of said cylindrical portion can lie closely against the wall of the hole and thus effectually prevent movement sidewise of the shank in the hole. This action will be aided by the upper flat surface of the point 3 which engages the under or outer surface of the part 12. Therefore, not only is side motion of the calk prevented, but its accidental withdrawal from place is most effectually resisted. The calk is also especially strong. It will be remembered that I have called attention to the fact that the upper surface of the point 3 of the calk is flat and I have set forth an advantage for this feature. In addition to the point to which attention has already been called I might add that this surface constitutes a shoulder to prevent said point 3 being driven into the sole or heel of the shoe and therefore prevents the upper pointed portion 11 of the shank from passing through

the sole or heel of the shoe and coming in contact with the foot of the wearer.

What I claim is:

A calk comprising an upwardly tapered shank and a point, said shank having a series of superposed annular ribs of inverted frusto-conical form, the under surfaces of which are at right angles to the longitudinal axis of the shank and said ribs from the lowermost one being of progressively decreasing diameter toward the top of the shank and said shank having a head comprising a cylindrical portion and a tapered pointed portion surmounting said cylindrical portion.

In testimony whereof I affix my signature in presence of two witnesses.

JOHN B. MURPHY.
